DISPENSING CONTAINER

Donald Waber and Raymond Braunstein, Jr.,
Philadelphia, Pa.

Application May 26, 1951, Serial No. 228,414

9 Claims. (Cl. 206—42)

1

Our invention relates to a new and useful dispensing container which is neat in appearance and of small size so that it may be conveniently carried in a pocket of an article of wearing apparel, purse or the like.

One object of the present invention is to supplement and improve the structure disclosed in our copending application, Serial No. 190,478, filed October 17, 1950, to adapt it for holding and dispensing items in such forms as medical tablets, confectionery drops or lozenges, capsules or other elongated articles.

Another object of our invention is to produce a package which is sufficiently well sealed, during the non-dispensing periods, to prevent contamination of the contents from outside sources.

Another object of the invention is to construct the dispensing container in a manner to provide a substantially central exit, relative to the sides of the container, gradually diminishing laterally towards the mouth, and having a movable ejector to propel an article ahead of it and progressively restrict the exit perpendicularly to the bottom to function as a barrier to articles to the rear of said ejector.

Another object of the invention is to provide an agitator for stirring, moving or shifting the contents of the container subsequent to each dispensing operation.

Another object of the invention is to produce a dispensing container including a box-like or receptacle body having an opening at the top and one end with baffles inside of said body adjacent the open end thereof and partially or wholly oblique to the side walls and convergently extending to or towards said open end to provide a gradually diminishing exit or outlet, and a closure slidably mounted in an inclined plane sloping downwardly from the closed rear end of the body towards the front open end thereof and including a top and front for normally closing the respective top and front openings of the body and further provided with an ejector and an agitator. Such a construction is highly advantageous for the purposes for which it is intended because the dispensed articles are delivered, one at a time, from the approximate longitudinal center at one end of the container so that it can be readily employed by either right or left handed persons and the ejecting means gradually restricting the exit to prevent accidental displacement of other contents of the container which does not have to be inverted for dispensing purposes, and the agitator will shift the positions of the remaining contents to break any blocks at

2

the exit which may be caused by the wedging action of items remaining in the container.

A further object of this invention is to divide the interior of the body into two parallel compartments by a longitudinal partition, particularly adapting the device for dispensing capsules and similar shaped items, and to so locate the agitator and said partition relative to each other that said agitator functions as a gate under certain conditions to prevent passage of items from one compartment to the other and from a certain compartment to the exit until the other of said compartments is empty.

With the above and other objects in view this invention consists of the details of construction and combination of elements hereinafter set forth and then designated by the claims.

In order that those skilled in the art to which this invention appertains may understand how to make and use the same we will describe its construction in detail referring by numerals to the accompanying drawing forming a part hereof, in which:

Fig. 1 is a perspective view of a dispensing container constructed in accordance with the invention and shown in a closed condition with dispensable articles therein.

Fig. 2 is a longitudinal sectional view on the line 2—2 of Fig. 1 and in a partially open or dispensing condition.

Fig. 3 is an enlarged fragmentary section on the line 3—3 of Fig. 1 showing one way in which the closure may be slidably mounted on the container body.

Fig. 4 is a similar view on the line 4—4 of Fig. 1 showing a clasp structure to normally maintain the closure in a closed position.

Fig. 5 is a similar view on the line 5—5 of Fig. 1 showing a type of joint that can be used between elements of the body and closure.

Fig. 6 is a transverse sectional view of the empty dispensing container on the line 6—6 of Fig. 1.

Fig. 7 is a perspective view of a slightly modified form of the dispensing container with the closure in an open position.

Fig. 8 is a similar view closed with dispensable articles shown therein in dotted lines.

Fig. 9 also is a similar view with the closure structure in a position during the initial movements of the dispensing operation.

Fig. 10 is a similar view at the end of the dispensing operation.

Fig. 11 is an enlarged fragmentary sectional view on the line 11—11 of Fig. 7.

Fig. 12 is a similar view on the line 12—12 of Fig. 8.

Fig. 13 also is a similar view on the line 13—13 of Fig. 8.

In describing our invention as herein embodied reference will be made first to the showing in Figs. 1 to 6, inclusive, wherein 15 and 16 represent, respectively, a box-like body and a closure produced from any suitable material having sufficient stiffness or rigidity to retain the shapes desired, such material may be opaque, translucent or transparent, according to the requirements or demands of the trade, and the material should have some inherent resiliency for certain purposes to be fully set forth below.

The box-like body 15 comprises a bottom 17 from which projects the upwardly extending perpendicular side walls 18 and rear wall 19 so that the top and front of the body are normally open. The upper edges of the side walls are, by preference, inclined in a downwardly sloping direction from the rear wall 19 towards and to the front open end.

Track grooves or runways 20 are shown as providing means for slidably mounting the closure 16 on the box-like body 15 and said runways, for the purposes of illustration, are depicted as formed in the inner faces of both side walls longitudinally thereof and inclined in a downwardly sloping direction from their rear to their forward portions or from the rear wall to the open front end of the body. When the upper edges of the side walls are similarly inclined the runways are parallel to said side wall upper edges and, preferably, contiguous thereto.

Within the body 15 are located stationary baffles 21 which extend from a location a short distance to the rear of the open front end of said body, at the side walls thereof, to said open front end and the construction of said baffles may be anything appropriate, such as strips of material fastened in place, to provide opposed surfaces oblique to the body side walls and constituting a gradually decreasing trap 22 and convergent towards the open front end of said body where said surfaces, or the baffles in particular, are spaced apart to form a somewhat restricted exit or mouth 22a of sufficient width to accommodate at least one item of the contents at a time.

The closure 16 includes a top wall 23 and pendant front wall 24 all substantially fitting within the confines of the body to close the normally open top and front end thereof, including the exit or mouth. Along the side edges of the top wall 23 of said closure are formed tongues or tracks 25, Fig. 3, which are slidably fitted into the runways 20 to permit the closure to slide longitudinally of the body. The tracks should snugly fit the runways to frictionally retain the parts against accidental relative movements although the closure can be held in a closed position by a suitable holding means.

For purposes of illustration, a holding means is shown as comprising a projection 26, Fig. 4, formed with and extending from the inner face of a side wall 18 of the body 15 for registration with a socket 27 in a side edge of the closure front wall 24. It is believed obvious that the locations of the projection and socket can be reversed and also that the holding means may be provided in multiple, one at each side of the body and closure. Again, it is believed apparent that one element of the holding means might be on the bottom wall of the body and the other ele-

ment on the lower edge of the front wall of the closure.

The lower edge of the front wall of the closure and the forward edge of the bottom wall of the body are provided with companion rabbet joint formations 28, Fig. 5, and similar rabbet joint formations 29, Fig. 2, are formed on the rear edge of the closure top wall and the upper edge of the body back wall to provide dirt proof joints when the container is closed.

An ejector 30, such as a transverse rib, depends from the underneath face of the closure top wall 23 adjacent to but spaced from the front wall 24 of said closure and the spacing is such that the distance between the ejector and said front wall is slightly greater than the diameter of the articles 31 to be dispensed, the articles herein shown only for purposes of illustration being medicinal or confectionery tablets. Also, the lower edge of said ejector is spaced a slightly greater distance from the bottom wall of the body, when the closure is in the closed position, than the thickness or height of the articles in the container. This allows an article resting on the bottom wall of the body, when the latter is tilted, to barely slide under the ejector and enter the trap 22 and as the closure is moved forwardly in its sloping plane relative to the body bottom wall and decrease the space between them sufficiently to prevent a following article from passing to the front of the ejector. The descent of the ejector towards the body bottom wall, as it is moved forwardly with the closure, will cause said ejector to engage the rear edge of the article in the trap and propel said article forwardly. At the same time said ejector assumes a position in front of the next succeeding article to prevent it and any other articles to the rear of the ejector from passing entirely through the trap.

An agitator 32, such as a substantially longitudinal rib, also depends from the underneath face of the top wall of the closure in a plane parallel or at a slight angle to the sides of the container. This agitator preferably extends from the front wall 24 to a location adjacent to and, by preference, slightly in front of the ejector and said agitator is of a depth to project below the tops of articles in the container within the trap or a short distance to the rear thereof. The lower edge of the agitator is spaced from the bottom wall of the body a sufficient distance to prevent interference with the forward sliding movement of the closure. The agitator is situated to one side of the trap adjacent one of the baffles 21 whereby said agitator cooperates with the other baffle to reduce the width of the inner end or entrance of the trap 22.

Should any of the articles 31 in the container become wedged in the trap at the entrance thereto after the ejection of one article, the agitator 32 will engage one of the articles and push it rearwardly, as the closure is retracted or moved rearwardly to its closed position, to loosen any jammed articles.

So that the closure may be readily slid to and fro by pressure of a person's thumb on the closure top wall a roughened area 33 may be provided on the exterior surface of said top wall. The forward or ejecting movement of the closure is limited by suitable stop means herein shown, for purposes of illustration only, as cooperating lugs 34 and 35. One of the stop lugs, as 34, is stationary and for convenience of illustration is shown as projecting from the interior face of one of the body side walls while

the other lug 35 is movable with and may depend from the underneath surface of the closure top wall 23. These stop lugs are so located, when the closure is retracted or closed, that they are spaced approximately the distance of the ejector back of or away from the exit 22a, preferably slightly more rather than less than said distance. This will insure a full opening of the exit to permit passage of an article therethrough just prior to the outward or forward movement of the closure being arrested by engagement of the movable lug with the stationary lug to prevent accidental disengagement of the closure from the container body. The upper edge of the lug 34 from its forward face and the lower edge of the lug 35 from its rear face are arcuately beveled to cause the lug 35 to ride over the lug 34 when the closure is initially assembled on the container body. The riding of one lug over the other is possible because of inherent resiliency or flexibility of the elements of the container or the material used in the construction thereof.

All exposed corners of the body and closure that do not have to be square, for operational purposes, are preferably rounded to reduce to a minimum the likelihood of the device catching in a person's clothing or on parts of a pocket, purse or other objects.

When it is desired to dispense the articles packaged in the container, the closure 16 projected forwardly with sufficient initial force to release the holding means 26—27 and thereafter with the necessary moderate force to simultaneously move the front end wall 24 away from and the ejector and agitator towards and to the exit 22a. As the ejector travels forwardly it will engage the rear of an article in the trap 22 and slide said article through and from the trap to and through the exit and beyond the forward edge of the body bottom wall where it may drop into a person's hand or mouth or into any receptacle or onto any surface directly beneath the forward end of the container. During the above described operation the ejector 30 continually descends towards or approaches the body bottom wall to gradually decrease the space between them and reduce the effective passageway perpendicularly relative to said body bottom wall to prevent the passage of the next succeeding or other article through the exit until the next forward stroke of the closure occurs.

During the dispensing operations, the container is generally held in an inclined position with the forward end thereof below the rear end to cause the articles therein to slide forwardly by gravity. As the closure is retracted or moved rearwardly the agitator 32 will contact one of the remaining articles which may be in line therewith to break any jam caused by wedging of the articles against one another and the baffles and assist in causing one of said articles to enter the trap. When the closure has reached its fully retracted position the ejector has been elevated to such an extent that a forwardly sliding article may pass beneath the ejector without interference and into the trap for future dispensation when the closure is again projected forwardly.

Referring now to the modification illustrated in Figs. 7 to 13, especially adapted for use with elongated articles, such as capsules, 15a and 16a represent, respectively, the box-like body and closure of any appropriate material having some

inherent resiliency and constructed in a manner to provide limited flexibility.

The box-like body, similar to that previously described, comprises a bottom 17a from which project the upwardly extending perpendicular side walls 18a and a rear wall 19a so that the top and front of the body are normally open. The upper edges of said side walls, preferably, are inclined in a downwardly sloping direction from the rear wall to the front open end of the body.

Track grooves or runways 20a are shown as providing means for slidably mounting the closure 16a on the box-like body 15a and said runways are depicted as formed in the inner faces of both side walls and inclined in a downwardly sloping direction from the rear wall to the open front end of the body.

Within the body are located opposed long and short baffles 21a and 21b, respectively, which extend from a location a short distance to the rear of the open end of said body, at the side walls thereof, forwardly towards said open end and in a generally oblique direction relative to said side walls. The longer baffle 21a extends all the way to the open end of the body and, preferably, has two different angular portions lengthwise thereof, the outer portion being slightly oblique or even substantially parallel to the body side walls while the inner end is more acutely pitched to provide part of a flaring entrance to a trap to be presently described.

The shorter baffle 21b terminates short of the open end of the body and in cooperation with the longer baffle forms a part of the trap 22b. The interior of the body 15a is divided into two longitudinal rather narrow compartments 36 and 37 by a longitudinal partition 38 extending from the rear wall to a location adjacent a vertical transverse plane at the inner ends of the baffles and the forward end of said partition is beveled on the side facing the longer baffle to assist in guiding articles from the compartment 36 into the trap.

The closure 16a includes the top wall 23a and pendant front wall 24a with tongues or tracks 25a along the longitudinal or side edges of said top wall all as previously described. Also as set forth in connection with the first described form of the device the structure is provided with a holding means, represented by the projection 26 and socket 27, and the rabbet joints 28 and 29.

The ejector 30a, such as a transverse rib, depends from the underneath face of the closure top wall 23a adjacent to but spaced from the front wall 24a of the closure and the spacing is such that the distance between said ejector and front wall is slightly greater than the length of one of the articles 31a to be dispensed which articles 31a are shown as capsules for purposes of illustration only. Also, the lower edge of said ejector is spaced a slightly greater distance from the bottom wall of the body, when the closure is in closed position, than the thickness or height of the articles in the container so that an article resting on the bottom of the body, when the latter is tilted, may slide under said ejector.

An agitator 32a, such as a substantially straight longitudinal rib, also depends from the underneath face of the top wall of the closure and extends from the front wall 24a to a location adjacent and, preferably, slightly past the location of the ejector in line with the vertical center of the compartment 37 and the rear end of said agitator is beveled at 39 on the side facing the

longer baffle 21a. This agitator, when the closure 16a is substantially or completely closed, forms the complete trap 22b having an exit at the forward open end of the device and functions as a gate for the outlet end of the compartment 37. When the closure is partly open, the beveled end of said agitator cooperates with the shorter baffle 21b to act as a guide from the compartment 37 to the trap between said agitator and the longer baffle 21a.

A roughened area 33a is provided on the exterior surface of the closure top wall to assist in securing a proper grip on the closure to slide the latter longitudinally. The forward or ejecting movement of the closure is limited by a stop means which, for purposes of illustration, is shown as comprised of the lugs 34 and 35 identical in construction and operation as previously set forth in connection with the form of the device first described.

When dispensing articles packaged in the type of container illustrated in Figs. 7 to 13, said container is tilted forwardly so that the foremost article in the compartment 36 will slide into the trap 22b between the longer baffle 21a and the agitator 32a, or one of said articles may already be in said trap. As the closure 16a is projected forwardly, the inclined travel thereof will cause the ejector 30a to gradually move closer to the bottom of the container and engage the rear end of the article in the trap for sliding said article forwardly to and through the exit from which location it may drop onto any surface below the container, such as the palm of a person's hand. The descent of the ejector towards the bottom of the container also decreases the space between the lower edge of said ejector and said bottom to prevent passage of the succeeding article or articles through the trap to the exit until the closure is completely retracted prior to the next dispensing operation. During the forward movement of the closure a second article may partially enter the trap but cannot pass out of the container because it is barred by the ejector and will be forced backward until said ejector is elevated above the bottom of the container to permit passage of the ejector over the article or the latter under said ejector.

The position of the agitator 32a when the closure is retracted prevents the articles in the compartment 37 from entering the trap and so long as there are any articles from the compartment 36 wholly or partially in the trap they bar the articles in said compartment 37 from entering said trap. Even if one of the articles in the compartment 37 has its forward end sticking into the entrance of the trap, such article will become wedged against one of the articles lying between the compartment 36 and said trap and will be held against further forward travel. Under such a condition the agitator will engage the article sticking out of the compartment 37 and push it back therein, as the closure is retracted, to free the article projecting from the compartment 36 and permit the last mentioned article to slide into the trap for subsequent dispensing. These operations are repeated until the articles in compartment 36 have been removed.

After all of the articles have been dispensed from the compartment 36, or the last one from said compartment is in the trap, the next forward movement of the closure will bring the beveled rear side edge 39 of the agitator substantially flush or in alignment with the inner

oblique surface of the shorter baffle 21b thereby opening a passageway from the compartment 37 to the trap. The foremost article from the compartment 37 partially enters the trap and as the closure is retracted the agitator will engage one side of said foremost article and push it transversely towards the opposite side whereby it will be lined up with the trap for unobstructed complete entrance thereinto. At about the same time 10 said agitator will engage the forward end of the next succeeding article in the compartment 37 and push it rearwardly and form a barrier to its entrance into the trap until the article then in the trap is being dispensed. Thereafter the 15 operations are repeated until all of the articles in the compartment 37 have been dispensed at which time the container will be empty.

In actual practice, the container is filled with 20 articles prior to the closure being assembled on the body. After the articles are placed in the container the closure is applied by sliding it endwise into the upper portion of the body from the forward end of the latter and by the use of a slight excessive pressure the stop lugs, because 25 of their beveled contiguous edges and the inherent flexibility of the body and closure, will be sprung past one another. Thereafter, as the closure is moved forwardly, two flat faces of said stop lugs contact and limit the ejecting movement of said closure to prevent accidental displacement thereof or an excessive stroke that might result in "spilling" of the articles. Each time an article is dispensed and the closure retracted the articles remaining in the container 30 will be dislodged or stirred about by the agitator to condition them for free sliding movements towards the exit to be subsequently positively forced from the container by the ejector.

Particular attention is called to the fact that 35 the exit is in the longitudinal center of the container thereby eliminating the necessity of tilting the same sidewise or shaking it about. Also the articles drop from the container exit by gravity in a natural manner thus overcoming the requirement of inverting the container prevalent in many dispensing containers. These features are exceedingly valuable in an instance where a person has only one hand in condition for use, either right or left, and desires to drop an article directly into the mouth. It should be apparent 45 that this type of dispensing container is highly efficient because of its easy manipulation by either right or left handed persons and by one forward and rearward stroke which can be accomplished by the use of one finger or thumb of one hand.

Of course we do not wish to be limited to the exact details of construction herein shown and described as these may be varied within the scope of the appended claims without departing from the spirit of our invention.

Having described our invention what we claim as new and useful is:

1. A dispensing container comprising a box-like body having a normally open top and front end and adapted to hold a plurality of articles to be separately and individually dispensed therefrom, the top of said body sloping downwardly and forwardly, means on the bottom of said body to direct the articles towards the longitudinal center of said body at the front end thereof when said front end is tilted downwardly and forming a restricted exit, a closure for the top and front end slidably attached to the top of said body and including top and front end walls, pendant means 60 on the underneath side of said top wall in spaced

adjacent relation to said front wall and to the bottom wall of the body, said pendant means gradually descending towards said bottom wall as the closure is moved forwardly to positively engage an article ahead of it and progressively decrease the space between said pendant means and the bottom wall of the body, and agitating means on the closure to engage any of the articles remaining in the container in the path of rearward travel of said agitating means as the closure is retracted to shift the remaining articles about within the container.

2. The dispensing container according to claim 1 wherein the space between the pendant means and the front end wall of the closure is slightly greater than one of the dimensions of each of the articles to be dispensed.

3. The dispensing container according to claim 1 wherein the space between the pendant means and the bottom wall of the body, when the closure is in its retracted position, is slightly greater than the height of the articles to be dispensed as they rest on said bottom wall.

4. The dispensing container according to claim 1, in combination with cooperating means on the body and closure to limit the forward sliding movements of said closure, and other cooperating means on the body and closure to temporarily hold the latter in its retracted position.

5. The dispensing container according to claim 1, in combination with a partition extending upwardly from and in the longitudinal center of the bottom of the body providing two parallel compartments, the agitating means being in alignment with only one of said compartments.

6. A dispensing container comprising a box-like body having a normally open top and front end and adapted to hold a plurality of articles to be individually dispensed therefrom, the top of said body sloping downwardly and forwardly, a pair of baffles on the inside of the body extending obliquely from the sides towards the open front end and forming a trap gradually diminishing in lateral dimensions to provide a restricted exit over the front edge of the bottom of the body, a unitary closure for the top and front end of and slidably attached to the top of said body, said closure including top and front end walls, an ejector depending from the underneath side of said top wall in spaced adjacent relation to said front wall of the closure and to the bottom wall of the body, said ejector gradually descending towards said bottom wall as the closure is projected forwardly, and an agitator depending from and extending lengthwise of the closure top wall from the front wall to a location adjacent the transverse plane of the forward face of the ejector and wholly to one side of the trap adjacent one of the baffles, said ejector adapted to propel an article through and from the trap to drop off of the forward edge of the bottom wall as the closure is projected and said agitator adapted to shift any articles within the container to the rear of the trap in the path of rearward travel of said agitator as the closure is retracted.

7. The dispensing container according to claim 6, in combination with a stop lug projecting from a side of the body within the same, and a companion stop lug projecting from the underneath side of the closure for cooperation with the first

65

70

mentioned stop lug to limit the forward movement of said closure.

8. The structure according to claim 7 wherein the lug on the side of the body is arcuately beveled on the upper edge from the front face and the lug on the closure is arcuately beveled on the lower edge from the rear face whereby said lugs may be readily forced past each other during the assembly of the container body and closure.

9. A dispensing container comprising a box-like body having a normally open top and front end, the top of said body sloping downwardly and forwardly, a longitudinal central partition extending from the rear closed end and terminating an appreciable distance short of the open front end, said partition providing parallel compartments to hold rows of articles to be individually dispensed, all of the articles being removed from one compartment prior to any being removed from the other compartment, the side of the forward end of the partition facing the compartment from which the articles are to be first removed being beveled to assist in guiding articles towards an exist, a long generally oblique baffle extending from the body side wall forming a part of the compartment from which the articles are first removed to the open end of said body, a short oblique baffle extending from the other body side wall towards but terminating short of said open front, the rear ends of both baffles meeting in a transverse plane forward of the front end of the partition, a closure for the top and front end slidably attached to the top of said body and including top and front end walls, an elongated agitator depending from the closure top wall in line with the approximate longitudinal center of the compartment from which the articles are to be last removed and extending from the front end wall to a location adjacent a transverse plane meeting the forward end of the partition when the closure is retracted and lying close to the forward end of the short baffle, the side of said agitator facing the longer baffle being beveled on approximately the same angle as that in which the short baffle is positioned, said baffles and agitator providing a gradually decreasing trap leading to a restricted exit over the front edge of the bottom of the body at the open end to guide articles towards the exit when the front end of the container is tilted downwardly, and a pendant ejector on the underneath side of said top wall in spaced adjacent relation to said front wall approximately equal to the length of a single dispensable article and also spaced from the bottom wall of the body, when the closure is retracted, a distance slightly greater than the height of a dispensable article, said ejector gradually approaching said bottom wall as the closure is projected forwardly to engage an article ahead of it and progressively decrease the space between the ejector and said bottom wall to hold a succeeding article to the rear of said ejector.

DONALD WABER.
